UNITED STATES PATENT OFFICE.

LELAND F. GOOD SPEED, OF MILWAUKEE, WISCONSIN, ASSIGNOR TO MILWAUKEE LOCOMOTIVE MANUFACTURING COMPANY, OF MILWAUKEE, WISCONSIN, A CORPORATION OF WISCONSIN.

GEARING FOR LOCOMOTIVES.

1,212,625.

Specification of Letters Patent. Patented Jan. 16, 1917.

Application filed January 18, 1912. Serial No. 671,852.

To all whom it may concern:

Be it known that I, LELAND F. GOOD SPEED, a citizen of the United States, residing at Milwaukee, in the county of Milwaukee and State of Wisconsin, have invented certain new and useful Improvements in Gearing for Locomotives, of which the following is a full, clear, concise, and exact description, reference being had to the accompanying drawings, forming a part of this specification.

My invention relates to gearing for locomotives which are propelled by internal combustion engines and which are of the type commonly employed in mines, lumberyards, brickyards, and similar industrial places, for hauling purposes. The prime essentials in a locomotive of this kind are power, compactness and control. So far as the power feature is concerned, the strength and efficiency of the parts must be considered. So far as the feature of compactness is concerned, the factors of construction and arrangement must be considered. And so far as the feature of control is concerned, the factor of mechanical responsiveness must be considered. My invention looks toward the satisfactory attainment of these various ends and is concerned with numerous subsidiary features which are dependent upon the particular use to which the locomotives are to be put. For instance, the employment of an internal combustion engine is highly desirable since fuel is consumed only when the machine is working and since it does not involve electrical track equipment, cumbersome in lumber and brick yards and similar places and positively dangerous in mines. However, the nature of operation of the internal combustion engine makes it necessary that certain precautions be taken when it is employed in mines, by reason of the gases which are almost invariably found there. Thus, certain measures must be taken to prevent any harmful intake for or exhaust from the engine, and I treat these features specifically in carrying out my present invention.

In the running of a locomotive of the kind to which my invention relates, it is highly desirable to be able to change speeds quickly and to be able to reverse suddenly and these are further features with which, it will be seen, I am particularly concerned.

Governing the engine by means of the throttle is also very important and I provide unique means for taking care of this feature, particularly adapted to the contemplated uses.

The weight of a locomotive, and the distribution of the weight upon the traction wheels, is important and the precise form of the body of my locomotive is of high efficiency in this respect. Not only does it give the desired weight, but it houses the various parts properly and compactly.

The various features of my invention are embodied in the construction illustrated in the accompanying drawings, in which—

Figure 1 is a side elevational view of the locomotive, parts being broken away and shown in section in order to reveal the interior construction; Fig. 2 is a plan view of the locomotive; Fig. 3 is a cross-sectional view taken substantially on the plane of the line 3—3 of Fig. 1 and looking in the direction indicated by the arrows; Fig. 4 is an isolated plan view of the clutch and change gear mechanism; Fig. 5 is a view similar to Fig. 4 except that it is shown in section taken on the horizontal axial plane; Fig. 6 is a more or less diagrammatic plan view of the locomotive, showing the cooling system for the engine; Fig. 7 is a vertical axial sectional view of a trap employed in the cooling system; Fig. 8 is a developed view showing the control for the clutch, change gears, and brake; Fig. 9 is an isolated detail view showing part of the controlling mechanism; and Fig. 10 is a view illustrating the throttle of the engine.

The traction wheels are shown at 11, 11 and the axles thereof are shown at 12, 12. Each of these axles carries a pair of journal boxes 13, 13, upon which the frame 14 rests, through the medium of springs 15, 15. The frame 14 is preferably in the form of a single piece casting and is fashioned to house the traction wheels, to carry and house all the other parts of the structure, and to provide a platform at the rear end for the accommodation of the operator.

Considerably more than the forward half of the frame 14 is supplemented by a skeleton superstructure 16 which carries and houses other operating parts. Toward the rear of the superstructure 16, the frame 14 is provided with the inwardly extending

supporting lugs 17, 17 upon which the crank case 18 of the internal combustion engine, which has been designated broadly by the reference character 19, rests. The crank 5 shaft of the engine is illustrated at 20. This shaft is operatively connected with a countershaft 21, by means of gears or other mechanism inclosed within the casing 22 and by means of this arrangement the exhaust 10 valves 23 are operated. The manifold for the engine is illustrated at 24 and the carbureter 25 is connected with this manifold, as indicated at 26. The inlet for this carbureter is illustrated at 27 and it will be seen 15 that it is covered with a screen 28 so that combustion on one side may not be transmitted to the other, in accordance with the principle involved in the operation of a Davy miner's lamp.

20 The crank shaft 20 is provided at its end with a pulley 29 which is connected, by means of a belt 30, with a pulley 31 on the shaft 32 of a water pump 33. This water pump forms part of a water cooling system 25 which will be described in detail hereinafter.

The exhaust pipes for the various cylinders of the engine are illustrated at 34, 34 and it will be seen that they are all connected 30 with the exhaust pipe 35 leading toward the front of the locomotive. This exhaust pipe 35, as best illustrated in Fig. 1, is provided with a relief valve 36, the function of which will be pointed out presently. Beyond the relief valve 36, the pipe 35 connects with a muffler 37 and the other end of the muffler, by means of a pipe 38, connected with the bottom of a chemical tank 39, the top of this chemical tank being connected 40 with the atmosphere. This chemical tank is provided for the accommodation of a lime solution through which the exhaust gases are passed when the locomotive is used in mines or any other places where gases are 45 likely to be ignited by contact. In this way the combustible factors in the exhaust vapors are "killed" before the fluid is passed on to the surrounding atmosphere. The function of the relief valve 36 will now be 50 obtained since in the case of a back draw on the part of the engine the lime solution will not be drawn through the system, but the valve 36 will open to admit the atmosphere through the path of least resistance.

55 Under ordinary circumstances, the valve 36 remains closed and it will be seen that the valve is simply constructed to allow gravity to effect this normal position.

60 The gasoline reservoirs 40, 40 are hung in convenient positions upon the skeleton superstructure and are connected by means of any suitable piping (not shown) with the carbureter.

65 The radiators 41, 41 are also hung in suitable positions upon the skeleton superstruc-

ture and are connected together and with water jackets surrounding the cylinders of the engine by means of piping 42, 42. The pump 33, which has hereinbefore been referred to, is connected up in this piping, 70 as is also a strainer 43, which is shown in detail in Fig. 7. It will be seen that it comprises a downwardly extending trap 44 which houses a tubular screen 45. The water is fed to the inside of the screen and is 75 withdrawn from the outside thereof. The bottom of the trap is provided with a cap 46 which may be removed to relieve the strainer of any collected impurities. It will be seen, by reason of the skeleton superstructure, that the radiators are exposed to the air, and while the specific form of these radiators does not comprise part of my present invention, it will be understood that the water is passed over cooling surfaces which 80 are exposed to the cold air. As a matter of protection, and still allowing for proper circulation, the open parts of the skeleton superstructure are closed by means of screens 47, 47, as illustrated in Figs. 1, 2 85 and 3.

The front end of the engine shaft 20 is provided with a fly wheel 48 which, as illustrated in Fig. 5, is secured to the end thereof by means of bolts 49, 49. This fly wheel is provided upon its forward face with the diametrical slot 50 in which the ends of a yoke 51, carried by the main shaft of a transmission mechanism to be described presently, are disposed. The purpose of this 90 arrangement will be described presently.

In front of the fly wheel 48 a heavy cradle 52 is mounted upon the frame 14 and it is this cradle that carries the clutch and change gear mechanism. This cradle 52 is 95 provided upon its longitudinal axis with three journal boxes 53, 54 and 55, the box 54 being in the middle and the others being at the ends. The main shaft 56 of the transmission mechanism is mounted in these 100 journal boxes and it is this shaft that carries the yoke 51. The shaft 56 is in alignment 105 with the shaft 20 of the engine and, the yoke 51 being secure upon the shaft 56, it is evident that the rotation of the shaft 20 will 110 be transmitted to the shaft 56 by reason of the engagement of the sides of the slot in the fly wheel with the ends of the yoke. The yoke ends are provided with wearing 115 parts 57, for obvious reasons.

120 Each of the bearings 53, 54 and 55 are provided with a bushing 58, these bushings providing partly for the direct support of the main transmission shaft and, as well, for the sleeves surrounding the shaft, as 125 will be pointed out hereinafter. Just the inside of each of the bushings 58 to the shaft 56 carries a frusto-conical fiber clutch member 59 which is clamped between plates 60 and 61, threaded upon the shaft, and which 130

is held rigidly with the shaft by means of any suitable key mechanism. The fiber element is confined in a spool 62 composed of two parts bolted together and it will be seen that the peripheral surface of the clutch member is a fiber one. The clutch members 59 converge toward each other and each of them is disposed within a correspondingly shaped shell 63 carried upon a yoke 64 extending from a sleeve 65 surrounding the shaft 56 and disposed within the bushing 58. Each of said shells 63 is provided with a face plate 66, bolted thereto by means of bolts 67, 67, this face plate having a central opening large enough so that the shaft 56 can pass therethrough without contact. The rear face plate 66 carries the beveled pinion 68 and the front face plate carries the pinion 69. Each of these pinions has a central opening of such size that the shaft 56 may pass therethrough without contact and has a concentric sleeve 70 extending forwardly therefrom. Each sleeve 70 is set in a bushing 71 mounted in the bearing 54. It will be seen that the two sleeves 70 are separate from each other, so far as rotation is concerned, and ball bearings 72, 72 are provided to prevent friction at the ends of said sleeves. It will now be understood that the shaft 56, carrying the two fiber clutch elements, is capable of longitudinal shifting. There are three effective positions: First, the normal position, that shown in Fig. 5, where neither of the fiber elements is in contact with the interior surface of its respective shell, second, the position wherein the forward fiber element is in contact with its shell, so that the pinion 69 will rotate, and, third, that position in which the rear element is in contact with its shell so that the pinion 68 will rotate. It will be seen that when one of said fiber elements is in contact with its shell, the other cannot be. It will be noted further that in whichever position the shaft 56 is brought, it will always be in operative relation with the engine shaft by reason of the fact that the slot and yoke arrangement 50 and 51, which has been described, admits of such longitudinal displacement without disturbing the angular relation.

The manner in which the shifting of the rotation from the pinion 68 to the pinion 69 and vice versa is secured, will now be described. The shaft 56 extends forwardly a short distance beyond the journal box 55 and there it is provided with a reduced end upon which a wearing collar 73 is clamped by means of nuts 74, 74. This collar is rounded by another collar 75 and between these two collars the ball races 76, 76 are provided. The collar or ring 75 is provided with trunnions 77, 77, as shown in detail in Fig. 9, and these trunnions are mounted 65 in the opposite sides of a yoke portion 78 of a lever 79 which is pivoted at 80 to an extension 81 from the frame piece 52. The lever 79 carries at its end a sleeve 82 which is internally screw-threaded for the reception of the screw-threaded end of the controlling rod 83 which, as shown in Fig. 1, extends from the lever 79 rearwardly and slightly upwardly to the operator's position. The controlling rod 83 is mounted within a sleeve 84, which will be referred to later and which itself is mounted in a bearing part 85 on the superstructure 16 of the frame. At its rear end the rod 83 is provided with a hand wheel 86 and it will now be seen that when it is turned in one direction or the other, it will result in the swinging of the lever 79 about the pivot 80. This shifts the shaft 56 of the transmission in one direction or the other and results in throwing in of one of the clutches. When the hand wheel is turned in one direction the lever 79 is drawn rearwardly to throw the forward clutch in and when it is turned in the other direction it is swung forwardly to throw the rearward clutch in. It will be remembered that only one or the other of the two pinions 68, 69 can be in operative connection with the shaft 56 at one time. These pinions are both constantly in mesh with a beveled gear 87 which is mounted upon a shaft 88 extending at right angles to the shaft 56 and in the same plane therewith. This shaft 88 is surrounded by a pair of bushings 89, 89, which in turn are surrounded by a sleeve 90. This sleeve 90 carries a collar 91 which bears, through the medium of ball bearings, in a bearing 92 on the frame 52. The shaft 88 extends beyond the sleeve 90 as clearly shown in Fig. 5, and is journaled in a bearing 93 in the frame 52, which forms part of a transmission box containing the change gears to be described presently. This box is indicated by the reference character 94 and is provided with an opening in the top which is closed by a cover 95 as illustrated in Fig. 2.

Referring again to Fig. 5 and to Fig. 4, it will be seen that the sleeve 90 has the gear 96 rigidly secured thereto. Mounted in bearings 97, 98 in the walls of the box 94 is a shaft 99, set parallel to the shaft 88. This shaft is surrounded by a bushing 100 which carries a sleeve 101 having the gear 102 meshing with the gear 96. The shaft 88 has a gear 103 keyed thereto and this gear meshes with a gear 104 mounted to revolve upon the shaft 99 which is stationary. The sleeve 90 is provided with a clutch collar 105 which rotates therewith but which may be moved longitudinally thereon, and the sleeve 101 is provided with a clutch collar 106 which rotates therewith but which is movable longitudinally thereon. Each of the gears 103 and 104 is provided with clutch teeth 107 and each of the clutch col-

lars 105, 106 is provided with clutch teeth 108 which are adapted to coöperate with the teeth 107.

The box 94 is provided with a vertical shaft 109 set midway between the shafts 88 and 99. This shaft carries a double-armed lever 110 and each arm of this lever is provided at its end with a loop 111 into which a pin 112 extending from a collar 113 5 is set upon the clutch collar 105 or 106 as the case may be, as clearly illustrated in Fig. 5. Outside the box the shaft 109 is provided with an arm 114 and it will now appear that when the arm is thrown in one direction the gear 104 and clutch collar 106 will be in operative relation and when the arm is thrown in the other direction the gear 103 and collar 105 will be in operative 10 relation. The arrangements are alternative 15 and only one can be in use at a time. It will thus be seen that the drive from the shaft 56 may be either through the shaft 88, gear 103, clutch axle 105, and sleeve 90, which is the high speed arrangement, or it 20 may be through the shaft 88, gear 103, gear 104, clutch collar 106, sleeve 101, gear 102, gear 96, and collar 90, which is the low speed 25 arrangement, the gear ratios being proper for this purpose. The arm 114 is connected, 30 by means of a rod 115; extending rearwardly therefrom, with a lever 116 pivoted at 117 to a part of the frame near the operator's position at the rear of the machine. By moving this lever one way or the other the 35 shaft 109 is shifted in the manner just described.

The sleeve 90 carries the driving sprocket 118 which, by means of a chain 119 is connected with a sprocket on the front axle. 40 This axle carries another sprocket wheel 121 which by means of a chain 122 is connected with a sprocket 123 on the rear axle.

Associated with each of the traction wheels 11 is a brake shoe at 124 which is loosely 45 hung from the frame work by means of the hanger 125. These brake-shoes have each pivoted thereto a lever 126 and these levers are connected by means of a rod 127. The forward lever 126 has its other arm 50 engaging with a part of the frame work and the rearward lever 126 has its other arm connected, by means of the rod 128, with a gear segment 129 mounted at 130 upon the frame work. This segment meshes with a 55 worm 131 carried upon the sleeve 84 and the outer end of the sleeve carries a hand wheel 132. It will now appear that when the hand wheel is turned the segment 129 is moved to set the brakes or to release them 60 as the case may be.

In Fig. 8 I illustrate a modified arrangement which does away with the controlling lever 116. In this modified arrangement the 65 analogous parts of the transmission and brake are lettered to correspond with the

parts of the arrangement which has been described and it will be seen that the difference lies in the use of a sleeve 133 which is disposed between the rod 83 and the sleeve 84. This sleeve is capable of longitudinal movement upon the rod 83, but it is splined thereon as illustrated at 134 so that it rotates therewith. In this case the hand wheel 86 is mounted upon the sleeve 133 and it will be seen that so far as the angular movement 70 of the shaft is concerned there is identically the same operation as in the case of the form already described. However, it is possible to shift the sleeve 133, as indicated in dotted lines in Fig. 8, and this shifting is utilized 75 by connecting the sleeve 133 with the shaft 109 of the change gear mechanism by means of an annular groove 135, bell crank lever 136 and a connecting link 137. It will now be seen that as the hand wheel 86 is shifted 80 forward and back it secures the gear changes already described, and this without interfering with its function to control the clutch.

A further feature of my invention is 85 illustrated in Fig. 10, where I have illustrated the engine and the carburetor. The throttle lever for the carburetor is indicated at 138 and it will be seen that it is associated with the governor 139 of the engine by 90 means of connecting links 140. The governor balls are held together by means of a spring 141 and when they are at their inner limit the throttle is wide open. A rod 142 substantially at right angles to the mid-position of the throttle lever 138 passes through the throttle lever and is provided with a collar 143 on one side of the throttle lever and a collar 144 on the other side thereof. A coil spring 145 is disposed between 95 the lever 138 and the collar 143 and a similar spring 146 is disposed between the lever 138 and the collar 144. The rod 142 connects with one arm of the governor crank lever 147, the other arm of which, by means 100 of a link 148, connects with the adjusting lever 149 clamped upon its pivot 150 and held in any position thereon by friction. It will be seen that by moving the lever in one direction or the other the action of the 105 spring 141 of the governor may be either aided or subtracted from and in this way the speed of the engine is controlled. This lever is conveniently at the operator's position and he may move the lever to one extreme to increase the effect of the spring 141 and to increase the speed of the engine, or he may move the lever to the other extreme to reduce the effect of the spring 141 and to 110 choose any intermediate position.

I claim as new and desire to secure by Letters Patent:

1. In gearing mechanism for a locomotive, a fly wheel having a slot and driven by 115

the driving motor, a longitudinally shiftable shaft, clutch members on said shaft, a gear associated with each clutch member, an operative connection for transmitting motion between said gears and the load, means carried by said shaft and disposed in said slot in said fly wheel for driving said shiftable shaft.

2. In gearing for a locomotive, a driving wheel having a flange, with diametrically disposed slots therein, a longitudinally shiftable shaft, clutch members operated by shifting said shaft, a spider on said shiftable shaft having arms movable in said slots and means driven by said shaft through said clutch member for transmitting motion to a power shaft.

3. In combination, a clutch, a lever for shifting said clutch, a screw-threaded part on said lever, an operating rod having a screw-threaded part coöperating with said first named screw-threaded part, change gears, a sleeve keyed on said rod, a hand wheel on said sleeve, and an operative connection between said sleeve and said change gears whereby shifting of the sleeve secures a change in gear relation and angular movement of said sleeve secures operation of the clutch.

4. In combination, a driving wheel having a flange and slots diametrically disposed in said flange, a longitudinally shiftable shaft, said shaft being substantially in line with the axis of said driving wheel, a spider on said shaft, said spider having arms disposed in said slots, clutch members on said shaft, said clutch members being brought into action by longitudinal move-

ment of said shaft, a lever for shifting said shaft, and means driven by said clutch members for alternately driving a power shaft. 40

5. In gearing for a locomotive, a driving wheel having a plurality of diametrically disposed slots, a longitudinally shiftable shaft, a spider having rigid arms disposed in said slots, said spider secured to said shaft, clutch members connected to said shaft, opposing clutch members associated with said first named clutch members, transmission mechanism, gearing between 50 said transmission mechanism and said opposing clutch members, and means to shift said shaft to operate said first named clutch members to bring one or the other of them into engagement with its respective opposing clutch member. 55

6. In gearing for a locomotive, a driving shaft, a clutch for said shaft, a lever for shifting said clutch, a screw-threaded part on said lever, an operating rod having a screw-threaded part, coöperating with said first-named screw-threaded part, change gears driven by said clutch, a sleeve keyed on said operating rod, an operating connection between said sleeve and said change 60 gears whereby shifting of the sleeve causes shifting of said change gears and means for moving said rod angularly to operate said clutch. 65

In witness whereof, I hereunto subscribe 70.
my name this 11th day of January, A. D.,
1912.

LELAND F. GOOD SPEED.

Witnesses:

ARTHUR H. BOETTCHER,
HARVEY L. HANSON.
